UNITED STATES PATENT OFFICE.

WESLEY A. PAUL, OF MOLINE, ILLINOIS, ASSIGNOR TO DEERE & COMPANY, OF OTTUMWA, IOWA, A CORPORATION OF ILLINOIS.

LEVER MECHANISM.

1,168,824.

Specification of Letters Patent. Patented Jan. 18, 1916.

Application filed March 27, 1914. Serial No. 827,610.

To all whom it may concern:

Be it known that I, WESLEY A. PAUL, a citizen of the United States, residing at Moline, in the county of Rock Island and 5 State of Illinois, have invented certain new and useful Improvements in Lever Mechanism, of which the following is a specification, reference being had therein to the accompanying drawing.

10 My invention relates to a lever mechanism illustrated as applied to a plow of a type employed as one of a gang attached to a common support.

15 The object of my invention is to provide a simple and effective means of limiting by adjustment the play of a lever, so that the movement of the object affected thereby is definitely fixed.

20 Referring to the drawings in which similar numerals indicate identical parts: Figure 1 is a side elevation of a plow showing my improvement. Fig. 2 is a detail section on the line $x-x$ of Fig. 1 and Fig. 3 is a detail section on the line $y-y$ of Fig. 1. 25 Fig. 4 is a detail view of one of the parts.

20 The plow-beam 1 is pivotally supported on the rear of a frame 2, common to plows of this description, and carries upon its rear end a plow body 3. A gage wheel 4 is supported on a wheel bail 5 pivotally mounted on a casting 6 secured to the beam 1. An upwardly and forwardly extending lever 5^a is also pivotally supported on the casting 6 on the same pivot as the wheel bail 5 and is 35 connected to the latter by a brace 7. A quadrant 8 is secured to the beam 1 in an upright position and is rigidly supported by braces 9 and 10 bolted to the casting 6 and extending to the upper end of the quadrant 8 on which they are secured by a suitable bolt.

40 A member 11 is movably supported on the quadrant 8; the upper end of the member 11 is formed at a right angle to the main portion and has thereon a slot 13 through 45 which the quadrant 8 projects. The end 12 is elongated and has a chamber 14 in which is a coil spring 15 bearing against the under side of the quadrant 8 and a cotter in the bottom of the chamber 14. The quadrant 50 8 is provided with notches 16 with any one of which the portion 12^a of the member 11 over the slot 13 is adapted to engage; the portion 12^a forming a tooth preferably integral with the end 12. Upon the lever 5^a 55 is secured a bracket 17 having an upper por-

tion 18 extending outwardly with an opening therein in which a lifting latch 19 is movable. A coil spring 20 encircles the lifting latch 19 between a shoulder 21 thereon and the portion 18. The lower end of the lifting 60 latch 19 is a hook 21^a adapted to engage with a lug 22 on the member 11; a latch rod 23 is hooked to the upper end of the lifting latch 19 and extends along the lever 5^a to a connection with a rocking grip 24 pivoted 65 on the upper end of said lever. On the opposite side of the lever 5^a is a latch 25 having its upper end projecting through an eye 26, forming part of a bolt utilized to secure the bracket 17 to the lever 5^a, and a rod 27 70 is connected to the latch 25 and to a rocking grip 28 on the upper end of the lever 5^a. Between the eye 26 and a pin 29 on the latch 25 is a coiled spring 30. The lower portion 75 31 of the latch 25 is bent at a right angle and projects through a slot 32 in the lever 5^a and similar slots in the bracket 17 and lifting latch 19, and is secured against displacement by a washer 33 on the end thereof, held in position by a pin or cotter, and a 80 washer 34 retained thereon in a similar manner against the lever 5^a. The portion 31 is adapted to engage with the notches of the quadrant and with a notch 35 in the member 11, the latter being movable along 85 the quadrant 8 on a pin 36 attached to the quadrant 8 and projecting through a slot 37 in the member 11 concentric with the quadrant 8.

85 An arm 38 is secured to the lever 5^a and 90 has connected thereto a coil spring 39 which extends forwardly to engagement with the hook end of a rod 40, the forward end of said rod extending through an opening in a bracket 41 secured on the quadrant 8 and threaded to engage with a hand nut 42 by the turning of which the tension of the spring 39 can be increased or diminished.

95 In the operation of my device it is to be supposed that the position of the parts shown is to regulate the depth of plowing determined, it is often necessary however to raise the plow from the soil to avoid an obstacle or for purposes of transportation, and it is desirable that when lowered into 100 operation the plow should again penetrate the soil to the same depth as before, the upward movement of the gage wheel being predetermined and limited for the required 105 depth of plowing. It will be seen that by 110

operating the grip 28 the latch will be raised from engagement with the notches in the quadrant 8 and the notch 35 of the member 11; consequently a downward movement of the lever 5^a, assisted by the tension of the spring 39, will force the gage wheel 4 downward raising the plow from the ground, and if it is desired to retain the plow in a suspended position, the latch 25 is engaged with either of the notches 43 on the lower part of the quadrant 8. In again lowering the plow after disengaging the latch 25 from a notch 43, the portion 31 of the latch 25 is adapted to travel on the quadrant 8 as the lever 5^a is moved upward, the movement of the lever continuing until the portion 31 reaches the notch 35 in the member 11 and the opposite notch on the quadrant 8, when the portion 31 will engage therewith fixing the position of the plow the same as before it was raised. On the member 11 I provide a shoulder or stop *b* against which the lever 5^a contacts when it is raised to its limit on the member 11 and the portion 31 of the latch 25 is in engagement with the notch 35.

When a greater or lesser depth of plowing is desired it is necessary to change the position of the member 11 on the quadrant 8, this I accomplish by operating the grip 24 to lift the latch 19, the hook 21 at the same time acting against the lug 22 and lifting the forward end of the member 11, simultaneously compressing the spring 15 and releasing the portion 12 from engagement with a notch of the quadrant 8. As the member 11 is raised it lifts the latch 25, releasing the portion 35 from engagement with a notch of the quadrant 8, but retaining it in the notch 35; a movement now of the lever 5^a in either direction will move the member 11 correspondingly until the desired position for a new depth of plowing is reached, then the grip 24 is released and the tooth 12^a of the member 11 engages with a notch of the quadrant 8 and is held in such engagement by the expansion of the spring 15, at the same time the portion 31 of the latch 25 also engaging with the teeth of the quadrant. From this new position of the member 11 the lever can be again utilized to raise the plow, with the assurance that when the plow is lowered it will penetrate no deeper than the depth determined, the upward movement of the lever 5 stopping as soon as the portion 31 of the latch 25 engages with the notch 35 and a notch of the quadrant 8. It will be noted that the member 11 and the quadrant 8 are of the same depth, consequently the teeth of the quadrant 8 are covered by the member 11, the notch 35 only permitting the portion 31 of the latch 25 to engage with the teeth of the quadrant 8.

I have shown and described my invention as applied to a plow, but it is plainly evident that it may be employed in numerous other

positions, where it is desirable that the limit of play of the lever can be varied.

What I claim is—

1. The combination with a lever and its quadrant, of means to lock the lever to the quadrant, a member on the quadrant and in engagement therewith and adapted to limit the movement of the lever, and means on the lever to disengage said member from the quadrant to change the position of said member by movement of the lever.

2. The combination with a lever and its notched quadrant, of means to lock the lever to the quadrant by engagement with any one of said notches, a member on the quadrant held in position by engagement with one of said notches and adapted to limit the movement of said lever, and means on the lever to disengage said member from the quadrant to change the position of said member by movement of the lever.

3. The combination with a lever and its notched quadrant, a member on the quadrant held in position by engagement with one of said notches, a notch in said member registrable with any one of the notches in the quadrant, means to close the remaining notches on the quadrant, means on said member to limit the movement of the lever, and a latch on the lever to engage with the notch in said member and the adjacent notch in the quadrant to lock the lever to the quadrant at the limit of its movement.

4. The combination of a lever and its notched quadrant, a member on the quadrant adapted to be moved to different positions by the lever, means on said member to retain it in varying positions on the quadrant, a notch in said member registrable with a notch in the quadrant, said member closing the remaining notches in the quadrant, a latch on said lever to engage with the notch in said member and the adjacent notch in the quadrant, and means on the lever to disengage said member and latch from the quadrant simultaneously.

5. The combination of a lever and its notched quadrant, a member on the quadrant adapted to be moved to different positions by the lever, means on said member to retain it in varying positions on the quadrant, a notch in said member registrable with any one of the notches in the quadrant, the remaining notches being closed by said member, a stop on said member to limit the movement of the lever, and a latch on the lever to engage with the notch in said member and the adjacent notch in the quadrant to lock the lever to the quadrant at the limit of its movement.

6. The combination of a lever and its notched quadrant, a movable member on the quadrant having a portion engaging with a notch on the quadrant to retain said member in position, a notch in said member reg-

istrable with any one of said notches in the quadrant, the remaining notches in the quadrant being closed by said member, a stop on said member to limit the movement 5 of the lever, and a latch on the lever to engage with the notch in said member and the adjacent notch in the quadrant when said lever contacts with the stop.

7. The combination of a lever and its 10 notched quadrant, a movable member on the quadrant having a notch registrable with any one of the notches on the quadrant, the remaining notches in the quadrant being closed by said member, a tooth on said member 15 to engage with a notch in the quadrant and held in said engagement by a spring on said member, a stop on said member to limit the movement of the lever, a latch on the lever to engage with the notch in said member 20 and the adjacent notch in the quadrant when said lever contacts with the stop, and a lifting latch on the lever adapted to raise said member and first latch from engagement with the quadrant to permit movement 25 of said member simultaneously with the movement of the lever.

8. The combination of a lever and its notched quadrant, a movable member on the quadrant, means on said member engaging 30 with a notch in the quadrant to hold said member in place, a notch in said member registrable with any one of the notches in the quadrant, a latch on the lever to engage with the notch in the member and the adjacent 35 notch in the quadrant, a lug on the member and a lifting latch adapted to engage with said lug and operable to raise said member and first latch from engagement with the quadrant to permit movement of said mem-

ber simultaneously with a movement of the 40 lever.

9. The combination of a lever and its notched quadrant, a movable member on said quadrant and having a longitudinal slot 45 therein, a pin on the quadrant projected through said slot and on which said member slides as it is moved, a notch in said member registrable with any one of the notches in the quadrant, said member closing the remaining notches in the quadrant, a latch on 50 the lever to engage the notch in the member and the adjacent notch in the slot, and means on the lever to raise said member out of engagement with the quadrant and to simultaneously release said lever from the 55 quadrant.

10. The combination of a lever and its notched quadrant, a member on the quadrant adapted to be moved at will by the lever, a notch in said member registrable with any 60 one of the notches in the quadrant, a slot in the lever, a bracket on said lever, a lifting latch supported on said bracket, slots in the bracket and lifting latch in alinement with the slot in the lever, a latch on the lever having its lower portion bent to project through said slots to engage with the notch in the member and adjacent notch in the quadrant, and means to disengage said latch from the 65 quadrant and said member to operate said 70 lever without moving the member.

In testimony whereof I affix my signature, in presence of two witnesses.
